UNITED STATES PATENT OFFICE.

FRIEDRICH CARL REINBOTH, OF BERLIN, GERMANY.

DEVICE FOR STRAPPING BOXES, CRATES, BALES, ETC.

Application filed March 14, 1922. Serial No. 543,737.

To all whom it may concern:

Be it known that I, FRIEDRICH CARL REINBOTH, a citizen of Germany, residing at 23 Ansbacherstrasse, Berlin, Germany, have invented certain new and useful Improvements in Devices for Strapping Boxes, Crates, Bales, etc. (for which I have filed application in Germany March 4, 1921), of which the following is a specification.

10 This invention relates in general to a device for strapping boxes, crates, bales, etc., by means of iron straps which are passed round the box, etc., and more particularly to devices by which an iron strap, after a 15 buckle has been attached to its one end, is pulled tight at its other end by means of a lever and, while being kept taut, has its second end made fast to the said buckle.

Known devices of this kind are all coupled with one drawback or another, or even have a number of disadvantages. With 20 some devices it is necessary to use iron straps of a certain length so that it is not possible to pass the strap around the box and cut it off from its coil only after the band has been 25 pulled taut and fastened. When a length of strap iron is cut off before the band is fastened the end piece by which the band is seized and pulled taut is wasted and the 30 strapping operation is troublesome.

With other devices of this kind there is the additional drawback that, to enable the band to be pulled taut, its end has to be threaded through the slot of a bar or bolt 35 prior to its being pulled taut by turning the bolt. With this arrangement a still greater length of iron strip is wasted, the operation is troublesome, and the uncoiling of the length of iron wound round the 40 bolt involves loss of time and labour.

With other devices which do not necessitate a section of strip being cut off from its coil prior to its being passed round the box and tautened, but which enable the strip to be inserted in a clamping device in which it is held fast and pulled tight bit by bit by 45 means of a lever, there is the disadvantage that the end of the iron strap has to be passed round the one edge of the buckle at an angle of almost 180° and has to be drawn round this edge which produces an extraordinary amount of friction and necessitates the application of a much stronger pull than that which is utilized for actually tightening the strap around the box. The force 50 which has thus to be exerted unnecessarily

is not only that by which the said friction has to be overcome but also an additional quota for bending the iron strap around the edge of the buckle and for stretching the 55 bent band section after it has been pulled round the said edge. A particularly disadvantageous feature of devices of this kind consists in the fact that the section of the iron strap at which the force is applied has 60 to be subjected to a much stronger pull than the part of the band that actually lies against and ties the box. In other words the tensile strength of the strap iron that is in contact with the box and secures the same 65 cannot be fully utilized. Hence, on account of the excessive stress to which the part of the strip that is used for pulling the band taut is subjected the iron strap used has to be stronger than is necessary for actually 70 securing the box. In other words the amount of material used and the costs are 75 unnecessarily great.

With other known devices the iron strap has to be weakened at the ends by holes for 80 rivets. This arrangement also involves the use of iron strap which is stouter than necessary in proportion as its section is weakened by the rivet holes.

Other devices are known by which a pull 85 is applied to only one end of the iron band. The tension applied with the same must therefore be transmitted to the section on the fourth side of the box through the sections lying against the three other sides of 90 the same. Since the iron band is held back by the friction at each edge of the box, the tension transmitted to the section that lies against the fourth side is considerably smaller than that at the end where the pull 95 is exerted. But as it is necessary to tighten the section at the fourth side sufficiently it follows that the force applied to the end where the pull is exerted is much greater than that which an adequate iron strap actually needs to resist. 100

By the present invention all the said drawbacks are removed. The iron strip has only to be cut off from its coil after it has been properly applied to the box, crate or bale, 105 and the tensile strength of the iron strap is fully utilized so that its section need not be made greater than is necessary for securing the box in an adequate manner.

The novel device is extraordinarily simple in use. 110

The invention is shown in the drawing in

which Fig. 1 is a side view of a device in position on a box and engaged in strapping the same,

Fig. 2 is a plan view of the main lever 5 with a portion of its handle broken off and its claw at its left end embracing the right hand edge of a strap buckle.

Fig. 3 is a perspective view of the main lever with the buckle-engaging claw pivoted 10 in its left end and its erect clamping member pivoted midway between the two ends of its plate, the clamping lever being removed from the clamping member.

Fig. 4 is a perspective view of the clamping lever.

Fig. 5 is a perspective view of a buckle with one end of a strap attached to its two right hand cross bars and the other end of the strap passed around its left hand cross 20 bar shortly before the final fastening on the same. The buckle in this figure is drawn on a larger scale than in the other figures.

Fig. 6 is a longitudinal section through the buckle-engaging claw at the left hand 25 end of the main lever on an enlarged scale, the free end of a strap being shown fixed to the right hand end of the buckle, and the end of the strap leading to its coil being shown in the act of being pulled taut.

Fig. 7 is a similar representation to Fig. 6 except that the iron strap, having been 30 fully tightened, is shown with its end that leads to its coil bent round the right hand edge of the left hand cross bar of the buckle 35 prior to the final fastening operation.

The device consists of the following parts: The main lever consists of a handle 8 with a plate 1 attached to its one end, the plate being provided with two lateral eyes 2 at its 40 left hand end in which the buckle-engaging claw 3 is journaled and with two lateral eyes 4 midway between two ends which receive the pivots of a clamping member 5 provided with a clamping surface 6 and two 45 lateral inverted hooks 7. The two lateral hooks 7 are adapted for receiving the lateral pivots or pins 9 of a clamping handle 10. When the pivots 9 are slipped into the hooks 7 the bottom clamping surface 11 of 50 the clamping handle rests upon the clamping surface 6 of the clamping member 5.

The buckle 12 shown in Figs. 1, 2 and 5-10 consists of a piece of flat iron 12 with slots 13 and 14 punched therein so as to form 55 three cross bars. Two lateral lugs 15 are struck up at the one end of the buckle as shown in Fig. 5. The right hand edge of the left hand cross bar and the left hand edge of the middle cross bar are serrated as 60 shown in Figs. 2 and 5. In some cases the serrations 16 at the left hand edge of the middle bar may be dispensed with.

The device is used in the following manner: A length 17 of iron strap, sufficient to 65 go round the case or bale, is unwound from

its coil, but not severed from the same. The strap 17 is threaded through the slot 14 of the buckle 12 and passed completely round the box, its free end being then again threaded through the slot 14 and made to 70 extend along the bottom surfaces of the middle and the right hand cross bars of the buckle 12 and then bent up at the right edge of the right hand cross bar and finally tucked into the slot 13 as shown in Fig. 5. 75 The main lever 1 is now moved up against the buckle with its claw 13 in engagement with the parts of the buckle that project laterally from both sides of the right hand end of the strap 17, Fig. 5. The end of the 80 iron strap located between the buckle and the coil is then placed between the hooks 7 and laid onto the clamping surface 6 of the clamping member 5. The clamping lever 10 is now inserted with its pivots 9 in the 85 hook 7. The handle 10 or the clamping lever is now pressed down to grip the strap between the clamping surfaces 11 and 6. On the downward motion of the handle 10 being continued the clamping member 5 90 will be swung round its pivots in the eyes 4 and the strap 17 will be pulled towards the right as indicated by dotted lines in Fig. 1. On the handle 10 now being turned to the left again the strap 17 between the 95 clamping surfaces will be released and these surfaces will slip along the strap and grip the same at another point when the handle 10 is swung to the right again. Thus the strap is taken up bit by bit when the handle 10 is oscillated to and fro. It is to be noted that the same motion by which the strap 17 is gripped between the clamping surfaces 6 and 11 and pulled towards the right 100 results in an equal pressure being exerted 105 towards the left of the pivots of the clamping member 5 in the lateral eyes 4, this pressure being thus transmitted through the claw 3 to the buckle 12 and through this buckle to the right hand end of the iron 110 strap. Hence, both ends of the strap are simultaneously pulled in opposite directions. The tension required for properly 115 tautening the iron strap is obtained by oscillating the handle 10 to and fro.

After the strap has been sufficiently tightened the handle 10 with the strap clamped between the clamping surfaces 11 and 6 is swung down into the position shown by broken lines in Fig. 1 in which it lies against 120 the handle 8. The two handles 10 and 8 are now both seized together and swung upwards around the pivots in the eyes 2, the left hand end of the strap being thereby brought into the position shown in Fig. 7 in 125 which it is bent round the right hand edge of the left hand cross bar of the buckle. The strap is then turned down towards the left and the lateral lugs 15 are then struck down by a hammer to clinch the strap on 130

the top surface of the left hand cross bar of the buckle.

I claim:

1. A device for strapping objects with metallic tape comprising, a buckle for receiving the said tape; a primary lever; a buckle-engaging claw pivoted in one end of the primary lever; a rocking member pivoted at a distance from the said end of the primary lever; a tape-clamping jaw and hooks on the rocking member; and a secondary handle with pivots adapted to engage with the said hooks and a second tape-clamping jaw adapted to cooperate with the first jaw.

2. A device for strapping objects with metallic tape comprising, a buckle with two slots for receiving the said tape and lateral tape-clinching lugs; a primary lever; a buckle-engaging claw pivoted in one end of the primary lever; a rocking member pivoted at a distance from the said end of the primary lever; a tape-clamping jaw and hooks on the rocking member; and a secondary handle with pivots adapted to en-

gage with the said hooks and a second tape-clamping jaw adapted to cooperate with the first jaw.

3. A device for strapping objects with metallic tape comprising, a buckle with two slots for receiving the said tape, lateral tape-clinching lugs, and serrations at an edge of one of the two said slots; a primary lever; a buckle-engaging claw pivoted in one end of the primary lever; a rocking member pivoted at a distance from the said end of the primary lever; a tape-clamping jaw and hooks on the rocking member; and a secondary handle with pivots adapted to engage with the said hooks and a second tape-clamping jaw adapted to cooperate with the first jaw.

In testimony whereof I have signed this specification in the presence of two witnesses.

FRIEDRICH CARL REINBOTH.
